WARP STOP-MOTION FOR LOOMS.

1,385,711.

Specification of Letters Patent. Patented July 26, 1921.

Application filed October 15, 1920. Serial No. 417,186.

To all whom it may concern:

Be it known that I, ALONZO E. RHOADES, a citizen of the United States, residing at Hopedale, in the county of Worcester and 5 State of Massachusetts, have invented an Improvement in Warp Stop-Motions for Looms, of which the following description, in connection with the accompanying drawings, is a specification, like characters on 10 the drawings representing like parts.

This invention relates to warp stop motions for looms, of that general character wherein the warp detectors are supported by the warp threads, and when any one of 15 the warp threads breaks or becomes too slack, the supported detector effects loom stoppage.

Various forms of warp stop motions have heretofore been proposed, and they naturally divide themselves into two general 20 types; first, that type wherein the warp detectors drop into the path of a vibrating feeler and stop its vibration when a warp thread becomes broken or unduly slack, and 25 second, that in which a dropped detector locks together two relatively movable toothed bars to effect loom stoppage. Since the warp detectors are supported by the warp threads, they must be light and not 30 injuriously affect the warp threads as they are drawn through the detectors during the weaving operation. In both types of warp stop motions, however, the warp detectors are subjected to strains which tend to injure 35 them. This is especially observable in the second type of warp stop motions, wherein there is usually employed a fixed and a relatively longitudinally movable toothed bar, which are locked together by a dropped 40 detector. In such type of warp stop motions, the longitudinally movable toothed bar is usually actuated by a vibrator or oscillating member having a spring connection with the movable bar, the construction being such 45 that when the movable bar is arrested by a dropped detector, the vibrator continues its movement and places additional stress upon the spring, which is transmitted through the movable bar to the dropped detector, with 50 the result that the detector itself is liable to be injured or broken.

One of the important features of the present invention, therefore, consists of a warp stop motion of the second type, wherein a 55 dropped warp detector is not injuriously

affected when it locks the relatively movable toothed bars from relative movement.

Another important feature of the present invention consists in an actuator which carries a rocker connected to the movable 60 toothed bar and controlling the operative and inoperative position of a latch device which is rendered effective to stop the loom when a warp thread breaks or becomes unduly slack.

The present invention also includes other novel features and combination of parts which will hereinafter be more fully described in connection with the accompanying drawings which illustrate one good practical form of the invention, wherein:

Fig. 1 is a perspective view of the warp stop motion with parts broken away, and showing more particularly the warp failure detecting means and associated parts;

Fig. 2 is a detail, partly in section, showing the means for operating a stopping mechanism on call for loom stoppage;

Fig. 3 is a detached detail, partly in section, showing guides for the latch-controlling bars;

Fig. 4 is a detached view of one of the latch-controlling bars;

Fig. 5 is a detached detail on an enlarged scale, showing more particularly the warp failure detecting means and the position of parts while the actuator is moving in one direction;

Fig. 6 is a view similar to that of Fig. 5, showing the position of parts when the actuator is moved in the opposite direction;

Fig. 7 is a side view showing the general relation between the warp failure detecting means and the loom change effecting means, or stopping mechanism; and

Fig. 8 is an enlarged detail, showing the stopping dog and its associated parts, for effecting loom stoppage.

The loom frame may be of any usual construction, and as indicated in the drawings 100 consists of the side frames 1, between which the warp failure detecting means is supported.

In the present instance of the invention, the side frames of the loom have extending 105 therefrom the brackets 2 preferably provided with a slot 3, and on which rest the arms or lugs 4 extending from the end portions 5 of the warp failure detecting mechanism. The arms 4 are preferably slotted 110

at 6 and are secured to the brackets 2 by suitable means such as the bolts 7. The construction above described is clearly shown in Fig. 1, at one side of the loom, and the other side is or may be substantially of the same character, the construction being such that the warp failure detecting means may be detached from the loom frame without disturbance of the parts between the warp failure detecting means and the stopping mechanism.

Secured to and extending between the end members 5 are the side members 8 over which the warp threads *a* extend. There are preferably two of the bars 8, one at the front and one at the back of the warp failure detecting means, and, if desired, additional bars may be supported between the sets of relatively movable toothed bars, as will presently be described, in order to afford a further support for the warp threads. Secured to each of the end members 5 of the warp failure detecting means are the fixed toothed bars 9, of which there may be one or more, or as shown in the present instance, there may be four of such fixed bars. The fixed bars 9 are secured to lugs 10 upstanding from the end members 5, and in the present instance they are secured to said lugs by means of the wing nuts 11, Fig. 1. Each of the fixed toothed bars 9 has associated with it a relatively movable toothed bar. In the present instance the fixed toothed bars 9 are provided with two rows of teeth 12, Fig. 1, which may be formed on the upstanding portions of the fixed bars 9 separated by an appropriate groove for receiving therein the relatively movable toothed bar 13. The teeth of the fixed and movable fixed bars may be variously formed, but in the present instance the teeth on the two bars are preferably disposed in an opposite direction, as indicated, though this is not essential. The construction is such that the movable toothed bars 13 may be reciprocated in the groove of the fixed toothed bars, as indicated in Fig. 1.

Associated with each of the fixed and movable toothed bars 9 and 13 are the warp detectors, adapted to be supported in normal or raised position by intact warp threads. The detectors may be of any usual construction suitable for the purpose, and in the present instance are shown as metal pieces 14 having an upper slotted portion 15 adapted to straddle or embrace the associated fixed and movable bars 9 and 13, Fig. 1. The detectors 14 are provided with the warp eyes 16 through which the warp threads *a* pass, the construction being as usual in warp stop motions, so that the warp detectors are normally held in raised or inoperative position by normally conditioned warp threads, and adapted to drop to lock the fixed and movable toothed bars from

relative longitudinal reciprocating movements when a warp thread breaks or becomes too slack. An actuator is associated with the warp failure detecting means, and in the present instance of the invention consists of an arm 17 which may be conveniently mounted for rocking movement at its lower end upon a shaft 18 supported in suitable bearings 19 extending from a bracket 20 secured to the loom frame. The shaft 18 is given a rocking movement to operate the actuator through suitably connected mechanism which, in the present instance of the invention, consists of a vibrator 21, the hub portion 22 of which is secured to the rock shaft 18, and the other end portion of which is formed bifurcated as at 23, and embraces a cam conveniently supported by a riser 26 on the loom frame. The cam is given rotative movement through the bevel gears 27 on the cam shaft 25, and 28 on the bottom or cam shaft 29, or other operating shaft in the loom, the construction being such that upon rotation of the shaft 29, the vibrator and perforce, the actuator 17, will be given their operating movements.

The actuator 17 carries one or more rockers for imparting the longitudinal reciprocating movements to the movable toothed bars, and for further controlling the means for effecting loom stoppage. In the present instance of the invention, the actuator 17 carries at its outer portion a stud 30 on which are mounted the two rockers 31. The upper portion of the rockers 31 are connected at 32 to the movable toothed bars 13. Extending downwardly from the rockers are the arms 33 to which are pivotally connected at 34 the latch-controlling slides 35 which pass through a guide 36 for directing their movements under the action of the actuator, as more clearly shown by Figs. 1 and 3.

Each of the latch-controlling slides 35 has a side extending pin 37 adapted to rest against the upwardly extending arm 38 of a latch device which, in the present instance of the invention, consists of a hub portion 39 mounted for rocking movement on the actuator 17 and having a hooked end portion 40, the construction being such that when the pins or studs 37 on the latch-controlling slides 35 hold the upper arms 38 of the latch device against the guide 36, the end portions 40 of the latch device will be held in an inoperative position with respect to a ledge 41 mounted for sliding movement on a support 42 extending from a bracket 43 secured to the loom frame, as best indicated in Figs. 1, 5 and 6.

The rocker 31, or in case more than one rocker is employed, each rocker, has extending therefrom a weight carrying arm 44 on which is adjustably mounted a weight 45 which normally acts on the rocker to hold

the pins or studs 37 of the latch-controlling slides with the upwardly extending arms 38 of the latch device against the guide 36, the construction being such that when the parts 5 are in the position last described, and the actuator 17 is rocked about its pivotal support, the hooked end portions 40 of the latch device will escape the ledge 41.

The ledge 41, hereinbefore mentioned, is 10 carried by an arm 46 pivotally connected at 47 to a lever 48 which is itself pivotally supported at 49 on the bracket 43 extending from the loom frame. A stop 50 on the bracket 43 normally limits movement of the 15 lever 48 in a contraclockwise direction, Figs. 1 and 5.

Extending through the upper slotted end 51 of the lever 48 is the pin 52, to which is secured a collar 53. The pin has mounted 20 on it the casing 54, and between the collar 53 and the end 55 of the casing is interposed the spring 56, the construction being such that movement of the lever 48 in a clockwise direction, Fig. 2, will impart yielding longitudinal movement to the pin 52 through the 25 spring 56.

Extending downwardly from the end member 5 of the warp failure detecting mechanism is a bracket 57, Fig. 2, carrying 30 a tube 58 which may be adjustably held in the bracket by a set screw 59, and the end of the pin 52 has a head 60 which extends into the tube 58 and bears against the end of a wire 61 which is inclosed within a flexible casing 62 which may be conveniently 35 formed as an inclosing wire which, while permitting longitudinal movement of the wire 61 within the casing 62, prevents buckling of the wire. The wire 61 is utilized 40 as the means for transmitting stopping movement to the loom stopping mechanism, which may be substantially as shown and described in the Burbank Patent, No. 1,240,666, dated September 18, 1917.

45 Mounted on the loom frame is a bracket 63, Fig. 7, through which extends the inclosed wire 61, the end of which bears against a setting plunger 64, Fig. 8. The plunger 64 controls the dog 65 which is normally 50 held in inoperative position with respect to a bunter 66 carried by the lay, by means of a spring 67, substantially as fully described in the Burbank patent, above mentioned. The dog 65 is pivotally supported at 68 on 55 a lever 69 pivotally mounted on the bracket 63 at 70. Pivotally supported on the loom frame at 71 is the knock-off lever 72 which is connected by a link 73 to the lever 69, as more fully described in the Burbank patent, 60 to which reference has been made, the construction being such that when the lever 48, hereinbefore described, is moved clockwise, Figs. 1 and 2, an intrust is transmitted to the inclosed wire 61 which places the dog 65 in the path of the bunter 66 of the lay 74

as it moves backwardly, to thereby knock-off the shipper lever and effect loom stoppage.

When the warp threads *a* are intact and under normal tension, they hold the warp detectors 14 in raised position as indicated 70 in Fig. 1, and the movable toothed bars 13 are free to move longitudinally and relatively to the fixed toothed bars 9 as the actuator 17 moves back and forth carrying with it the rocker or rockers. During such normal operation, the pins 37 hold the latch device with its hooked end portion 40 in inoperative position relative to the ledge 41. When, however, a warp thread breaks or 75 becomes too slack for proper weaving conditions, the supported warp detector drops and locks the fixed and movable toothed bars from relative movement, so that as the actuator 17 moves to the right, as indicated in Fig. 5, the now stationary toothed bar 13 80 will tilt or rock the rocker into the position indicated, thereby removing the pin 37 from the arm 38 of the latch device, and permit the associated latch to move into operative 85 position with respect to the ledge 41, as indicated in Fig. 5. On the return movement of the actuator 17, as indicated in Fig. 6, the latch device will move the lever 48 and effect endwise movement of the incased wire 90 95 61 to effect loom stoppage.

As hereinbefore noted, the warp detectors are light metal devices, and the weights 45 are so constructed and arranged with respect to the rocker to which the weight is associated, that when the movable toothed bar 100 13 is arrested by a dropped warp detector, and the actuator is moved to the right as indicated in Fig. 5, no increased strain or force is exerted against the dropped detector which might be calculated to injure it. In 105 other words, the effective force which prevents rocking movement of the rocker and its undisturbed movement with the actuator when its connected toothed bar is not obstructed, is not increased when the connected toothed bar is stopped by a dropped detector, as is usually the case with stop motions of this type, wherein the force exerted upon the movable toothed bar is effected by 110 spring means which yields when the movable bar is stopped and exerts an increasing force upon the toothed bar as its actuating means continues its actuating stroke. Moreover, by adjustment of the weight 45 on the carrying arm 44 of the rocker, the effective 115 movement exerted upon the movable toothed bar by the actuator may be regulated at will, and adjusted to the character of the warp detectors, so as not to effect injury thereto when one of such detectors obstructs movement to the movable bar. The weights 45 120 may be and usually are just sufficient to hold the rocker from rocking movement, and maintain the latch device in inoperative position during normal operation of the loom 125 130

when the threads are in normal condition, so that when the attached movable toothed bar is obstructed by a dropped detector, no injurious strain is transmitted to the detector.

- It may be desirable at times to remove the warp failure detecting means, or one of the movable toothed bars; and in order to facilitate this without disorganizing the warp stop motion, the movable toothed bars 13 may be connected to the rocker by a link 75 carrying a pin 76 which engages an open slot in the end portion of the movable bar 13. In case there are a number of movable bars,—four for instance, as indicated in the drawings, the pin 76 may be conveniently extended to engage the slots in the two bars so that by throwing up the link 75, the warp failure detecting means may be disassociated with the warp stop motion, without disturbance of any of the parts of the latter.

What is claimed is:—

1. In a warp stop motion for looms, the combination of a fixed and longitudinally movable toothed bar, a series of warp detectors which are hung upon and normally supported in raised position by the warp threads and constructed and arranged to lock the toothed bars together, an actuator, a rocker mounted on the actuator for movement therewith and for rocking movement thereon, connections between the rocker and movable toothed bar, means normally acting to hold the rocker from rocking movement while being moved with the actuator and permitting such rocking movement when the toothed bar is held from longitudinal movement by a warp detector dropped by a slack or broken warp thread, and means for stopping the loom when the rocker partakes of its rocking movement during movement of the actuator.

2. In a warp stop motion for looms, the combination of a fixed and a longitudinally movable toothed bar, a series of warp detectors which are hung upon and normally supported in raised position by the warp threads out of locking engagement with the fixed and movable toothed bars, an actuator, a rocker bodily movable by the actuator, connections between the rocker and the movable toothed bar, a weight which is connected to the rocker and normally holds it from rocking movement as it is bodily moved by the actuator and prevents rocking movement thereof until the movable toothed bar is stopped by a warp detector dropped by a slack or broken warp thread, and means rendered effective by rocking movement of the rocker for stopping the loom.

3. In a warp stop motion for looms, the combination of a fixed and a longitudinally movable toothed bar, a series of warp detectors which are hung upon and normally supported in raised position by the warp

threads out of engagement with the toothed bars, an actuator, a rocker bodily movable by the actuator, connections between the rocker and the movable toothed bar, a weight which is connected to the rocker and normally holds it from rocking movement as it is bodily moved by the actuator, a latch movable with the actuator, an arm carried by the rocker and normally acting under the influence of the weight to hold the latch in an inoperative position, and means actuated by the latch for stopping the loom when a warp detector is dropped by a warp thread into engagement with the teeth of the fixed and movable toothed bar.

4. In a warp stop motion for looms, the combination of toothed bars which are relatively movable longitudinally, a series of warp detectors which are hung upon and normally supported in raised position by the warp threads, an actuator having uniform movement, connections between the actuator and one of the toothed bars for transmitting movement to the bar, a weight which operates through the connections to permit the connected toothed bar to be stopped by and without injury to a dropped detector, and means for stopping the loom when the toothed bars are locked from relative movement by a warp detector which has been dropped by a warp thread.

5. In a warp stop motion for looms, the combination of toothed bars which are relatively movable longitudinally, a series of warp detectors which are hung upon and normally supported in raised position by the warp threads, an actuator having uniform movement, connections between the actuator and one of the toothed bars for transmitting movement to the bar, a weight which operates through the connections to permit the connected toothed bar to be stopped by and without injury to a dropped detector, a latch which is held in an inoperative position by the weight until the toothed bars are locked from relative movement, and means actuated by the latch for stopping the loom when the latch is freed from control of the weight.

6. In a warp stop motion for looms, the combination of toothed bars mounted for relative longitudinal movement, a series of warp detectors which are normally held raised by intact warp threads, an actuator for relatively moving the toothed bars, a rocker connected to the actuator and having an arm connected to one of the relatively movable toothed bars, a latch, a weight normally acting to hold the latch in an inoperative position and the rocker from rocking movement, and means actuated by the latch to stop the loom when the toothed bars are locked from relative movement by a detector that is dropped by a warp thread.

7. In a warp stop motion for looms, the

- combination of an actuator, a rocker connected to the actuator, an endwise movable toothed bar connected to the rocker for reciprocating movement thereby, a stop latch, 5 means connected to the rocker and acting to hold the stop latch in inoperative position until the rocker is rocked by obstruction to reciprocating movement of the toothed bar, and a series of warp detectors normally supported in raised position by the warp threads 10 and constructed and arranged to be dropped by a too slack or broken warp thread to lock the toothed bar from movement and cause the latch to effect loom stoppage.
- 15 8. In a warp stop motion for looms, the combination of toothed bars which are relatively movable longitudinally, a series of warp detectors normally supported in raised position by the warp threads for locking the 20 toothed bars from relative movement when a warp thread breaks or becomes too slack, an actuator, connections between the actuator and one of the relatively movable toothed bars which transmits to the connected 25 toothed bar the movement of the actuator, means operating through said connections with unvarying force to permit the toothed bar to be stopped by a warp detector without injurious effect on the detector when it 30 is dropped by its warp thread, and means for stopping the loom when the toothed bars are locked from relative movement.
9. In a warp stop motion for looms, the combination of fixed and movable toothed 35 bars, warp detectors which are hung upon and normally supported in raised position by the warp threads, an actuator, a rocker carried by the actuator and connected to the movable toothed bar, means normally acting 40 to hold the rocker from rocking movement as it is bodily moved by the actuator and permitting such locking movement without injury to a warp detector when the warp detector is dropped by a warp thread breaking or becoming too slack, and means for 45 stopping the loom when the rocker partakes of rocking movement.
10. In a warp stop motion for looms, the combination of fixed and movable toothed 50 bars, warp detectors, normally hung upon and held in raised position by the warp threads and constructed and arranged to lock the bars together when a warp thread breaks or becomes too slack, an actuator, a 55 rocker carried by the actuator and connected to the movable toothed bar, means which normally acts to prevent rocking movement of the rocker on the actuator when the movable toothed bar is not obstructed from endwise movement and permitting such rocking movement without injury to the warp detector when the fixed and movable toothed bars are locked from relative movement by a dropped detector, a latch which is held in inoperative position until the rocker partakes of its rocking movement and is then moved to operative position to stop the loom. 60
11. In a warp stop motion for looms, the combination of relatively fixed and longitudinally movable toothed bars, warp detectors normally supported in raised position and constructed and arranged to lock the bars together when the warp thread breaks or becomes too slack, an actuator for imparting longitudinal reciprocating movements to 70 the movable toothed bars, rocker arms and latches carried by the actuator, means connecting one end of the rocker arms to the movable toothed bars, means connected to the other ends of the rocker arms for normally holding the latches in inoperative position when movement of the movable toothed bars is not obstructed and permitting movement of the associated latch to operative position when one of the toothed bars 75 is held from movement by a dropped warp detector, and means operated by an operatively positioned latch for stopping the loom. 80
12. In a warp stop motion for looms, the combination of fixed and movable toothed bars, warp detectors constructed and arranged to lock a fixed and movable toothed bar from relative movement when a warp thread breaks or becomes too slack, an actuator, a rocker arm mounted on and movable with the actuator, a latch device mounted on the actuator, a rod connected to the rocker, an adjustable weight connected to the rocker and acting to hold it from rocking movement and the latch device in an inoperative position until the movable bar is obstructed in its freedom of movement by a dropped detector, and means adapted to be operated by the operatively positioned latch 95 for stopping the loom. 100

In testimony whereof, I have signed my name to this specification.

ALONZO E. RHOADES.
